LADY'S HANDBAG

Leo M. Cohan, Highland Park, Ill.

Application February 1, 1949, Serial No. 612

Term of patent 14 years

(Cl. D87—3)

To all whom it may concern:

Be it known that I, Leo M. Cohan, a citizen of the United States, residing at Highland Park, in the county of Lake and State of Illinois, have invented a new, original, and ornamental Design for a Lady's Handbag, of which the following is a specification, reference being had to the accompanying drawing, forming a part thereof.

In the drawing—

Fig. 1 is a front perspective view of a lady's handbag, showing my new design; and

Fig. 2 is a rear perspective view.

The dominant feature of my design resides in the riveted pocket on the back combined with the flap on the front closed by a rivet-like snap and in association with the plural stitching around the edges of the handbag.

The conventional handle is shown in broken lines and is broken away for convenience of illustration.

I claim:

The ornamental design for a lady's handbag, as shown.

LEO M. COHAN.
